US0D1083334S

(12) United States Design Patent (10) Patent No.: US D1,083,334 S
(45) Date of Patent:  Jul. 15, 2025

(54) SHOE(71) Applicant: NIKE, Inc., Beaverton, OR (US)(72) Inventor: Benjamin Nethongkome, Beaverton, OR (US)

D329,941 S 10/1992 Hatfield
D330,797 S 11/1992 Lucas
D333,034 S 2/1993 McDonald
D334,278 S 3/1993 Greene
D335,387 S 5/1993 Smith
D335,761 S 5/1993 Smith

(73) Assignee: NIKE, Inc., Beaverton, OR (US)

FOREIGN PATENT DOCUMENTS

() Term: 15 Years

CN 308865663 * 11/2021
GB 6388854 * 9/2024

(21) Appl. No.: 29/964,661

FIG. 1 is a side view of a shoe showing my new design;
FIG. 2 is a front perspective view thereof;

FIG. 3 is a rear perspective view thereof;

FIG. 4 is an enlarged view of the claim as shown in FIG. 1
with environment removed for clarity purposes;

FIG. 5 is an enlarged view of the claim as shown in FIG. 2
with environment removed for clarity purposes; and,

FIG. 6 is an enlarged view of the claim as shown in FIG. 3
with environment removed for clarity purposes.

The broken lines depicting the remainder of the shoe form
no part of the claimed design.

1 Claim, 6 Drawing Sheets
